COMPASS HOLDER FOR SCUBA DIVERS

Owsley H. Brigham, 7510 Morningside Drive,
Indianapolis, Ind. 46240

Filed June 17, 1971, Ser. No. 154,259.

Term of patent 14 years

Int. Cl. D10—99

U.S. Cl. D52—6 B

Fig.1.

Fig.2.

Fig.3.

Fig.4.

Fig.5.

FIG. 1 is a top view of a compass holder for scuba divers showing my new design;

FIG. 2 is a side view thereof with parts of the strap broken away for convenience of illustration;

FIG. 3 is a bottom view of FIG. 2;

FIG. 4 is an end view as seen from the left of FIG. 2; and

FIG. 5 is an end view as seen from the right of FIG. 2.

The side opposite to FIG. 2 presents a mirror image thereof.

I claim:

The ornamental design for a compass holder for scuba divers, as shown and described.
